UNITED STATES PATENT OFFICE

VINCENT V. VEENSCHOTEN, OF ERIE, PENNSYLVANIA, ASSIGNOR TO NORTHERN EQUIPMENT COMPANY, OF ERIE, PENNSYLVANIA, A CORPORATION OF PENNSYLVANIA

PUMP GOVERNOR

Application filed June 30, 1928. Serial No. 289,356.

This invention relates to pump governors and, particularly, to governors which are applicable to steam pumps for pumping water where it is desired to control the pressure on the water which is being delivered. The invention has for its object certain improvements relating to pump governors which make more effective the proper discharge pressure, particularly with pumps which are 10 delivering water where the back pressure is more or less variable.

Of the accompanying drawings, Fig. 1 is a more or less diagrammatic elevation of a power plant system which illustrates mechanism which embodies the features of my invention; Fig. 2 is an enlarged side elevation of the pump governor of the system; Fig. 3 is a sectional view along the line 3—3 of Fig. 2; and Fig. 4 is a sectional view along the 20 line 4—4 of Fig. 3.

The system illustrated comprises a steam boiler 10 which receives water through a pipe 11 from a pump 12, the pump being operated by a steam engine 13 receiving steam 25 through a pipe 14, the speed of the engine being controlled by the governor 15.

The pump governor comprises a casing 16, mounted in the chamber 19 of which is a compressible chamber 17, ordinarily called a 30 sylphon bellows. The bellows receives steam under the pressure of the boiler through a pipe 18 which is connected to the steam pipe 14, and the chamber 19, in which the bellows is mounted, receives water pressure through 35 a pipe 20 which is connected to the discharge pipe 21 of the steam pump, or to the inlet of the feed-water valve 22 of the boiler system.

Mounted in the steam pipe 14 is a steam 40 valve casing 23 which controls the operation of the pump. In this valve is a valve plunger 24 which is operatively connected with the sylphon bellows 17. The upper end of the bellows is fixed to the casing 16 and the 45 lower and free end is connected, by means of a stem 25, an arm 26, and a shaft 27, with an arm 30 outside of the casing 16. The arm 30 is connected, by means of a link 29, with an arm 28 which, by means of a shaft 31, and an arm 32, is connected to the stem 33

of the valve 24. As a consequence of these connections, when the free end of the bellows moves upwardly, the valve 24 will be lowered so as to close the ports 35 more or less, depending upon the movement of the bellows end. On the other hand, when the bellows end is lowered, the valve will be elevated somewhat, opening more the ports.

In operation, when the water pressure in the discharge pipe of the pump increases above the desired amount, the water pressure in the chamber 19 will compress the bellows elevating the lower end thereof and, thus, closing somewhat the valve ports 35 and reducing the power of the pump and the pressure of the water delivered thereby, bringing the pressure back to the desired amount. On the other hand, if the pressure in the discharge pipe decreases below the desired amount, the steam pressure in the chamber of the bellows will extend the bellows, forcing the free end downwardly and, thus, opening somewhat more the ports 35. Fixed to the shaft 31 is an arm 36 bearing a weight 37. This weight takes up all loose play of the system and elevates the plunger when the water pressure allows the free end of the bellows to move downwardly.

In case of an increase in pressure of the steam in the boiler and, hence, in the pipe 14, as there is then an increase in back pressure on the water flowing into the boiler, it is desirable to increase the pressure in the discharge pipe of the pump. In these conditions, the increased pressure of the steam extends the bellows and allows the weight to open somewhat more the ports of the valve 24 and, thus, increases the power of the pump. Conversely, as the steam pressure decreases, the water pressure will compress the bellows and the ports of the valve will be closed more or less.

It has become more and more desirable to increase the sensitiveness of the steam valve of the pump with reference to the variations in pressure of the water and steam, particularly in view of the enormous steam pressures and capacities of modern boilers, and my invention is directed towards increasing this sensitiveness beyond that ordinarily attained.

- By the use of the rotating shafts 27 and 31 passing through the respective stuffing boxes 40 and 41, the force required to operate the shafts is very greatly decreased with reference to the force required to operate shaft stems which slide longitudinally through the boxes. The force required to operate rotating shafts is so slight that very slight changes in the steam or water pressures will have full effect in operating the pump steam valve.
- In order to further increase the sensitiveness of the governor, I provide ball bearings 42 and 43 to oppose the thrust on the shafts 27 and 31, due to the pressure on the inner ends of the shafts in the casings 44 and 45. In view of the enormous pressures which are frequently generated in modern boiler systems, the thrust on these shafts is very great, often five hundred pounds or more, and ball bearings to overcome this increase materially the sensitiveness of the governors. The ball bearing casings 46 are supported by brackets 47, and collars 48, fixed to the respective shafts 27 and 31, allow the bearings to carry the outward thrust on the shafts.
- It will be noticed that the bellows casing 16 and the valve casing 23 are entirely independent of each other. Hence, the controlling pressures on the bellows are in no way affected by pressures in the valve casing; and the use of the rotating shafts or spindles not only enormously decreases the force required to operate through the stuffing boxes, but also allows any desired leverage controlling the relative movement of the free end of the bellows and the valve. This also allows a relatively large bellows with a moderate weight.
- I have provided special stuffing box means to be used with either one or both of the rotary shafts or valve stems 27 and 31. This comprises a split bushing 50 which is inserted in the gland 51 so that the bushing can be removed from the shaft without removing the collar 48 from the shaft. I also provide a nut 49 which is screwed on to the base 52 of the bracket 47, thus holding the bracket rigidly in place on the stuffing box 41. The advantage of this arrangement is that the nut 49 can be backed off, and, after the arm 30 is removed from the outer end of the shaft, the entire bracket housing 47 and gland 51 can be removed from the shaft. The split bushing 50 is inserted to allow the gland 51 to pass over the collar 48. This construction makes it very easy to remove the packing from the deep stuffing box and for replacing it with new packing. After the packing is in place, the entire assembly is slipped over the shaft and the nut 49 is screwed into place.
- I claim as my invention:
1. A pump governor comprising a valve casing, a valve mounted in said casing, a rotary shaft projecting into and out from said casing and being operatively connected with said valve, a second casing fixed to said valve casing, a rotary shaft projecting into and out from said second casing, means operatively connecting the outer ends of said shafts, means in said second casing for operating said second shaft, and ball bearings limiting outward movement of said shafts.
  2. A pump governor comprising a valve casing, a valve mounted in said casing, a rotary spindle projecting into and out from said casing, an arm projecting angularly from the inner portion of said spindle, said arm being operatively connected with said valve, a second casing fixed to said valve casing, a rotary spindle projecting into and out from said second casing, means operatively connecting the outer ends of said spindles, means in said second casing for operating the spindle of said casing, and thrust bearings limiting the outward movement of said spindles.
